UNITED STATES PATENT OFFICE.

JOSEF PROKOP, OF PARDUBICE, CZECHO-SLOVAKIA.

TREATMENT OF CEREALS.

Application filed December 27, 1920. Serial No. 433,476.

To all whom it may concern:

Be it known that I, JOSEF PROKOP, a citizen of the Czecho-Slovak Republic, residing at Pardubice, Czecho-Slovakia, have invented certain new and useful Improvements in the Treatment of Cereals, of which the following is a specification.

My invention relates to the treatment of cereals and more especially to a method of 10 and apparatus for husking, sprouting, dis-budding and polishing granular material and quite especially grain of all kinds.

The essential feature of my invention resides in the material to be treated being conveyed along an apparatus and this within a box in such wise that it will come to bear up 15 against a section of a cylinder surface and will thus be taken along by the rough surface of the revolving cylinder in the direction in which this latter rotates, and will 20 consequently be carried upward, where by aid of a finger or another rotary cylinder the grain is caught and raised in order to enable it then by its own proper weight to 25 descend in the opposite direction on and above the ascending layer of grain, till it is again lead by a lower transverse wall to the cylinder surface to be once again taken along in the manner aforesaid. By these 30 means, the grain is caused to circulate continuously within the box, resulting in its being operated upon in a thoroughly uniform manner.

In the drawings affixed to this specification and forming part thereof several modifications of an apparatus suitable for carrying this improved method into effect and embodying my invention are illustrated by way of example. In the drawings

40 Figs. 1 and 2 are vertical sections of one modification, and

Fig. 3 is a pertinent horizontal section, while

Fig. 4 is a vertical section of a modified 45 form of construction.

Referring to the drawings, the apparatus disclosed in Figs. 1 to 3 comprises a cylinder 2 having a more or less rough surface and being adapted to revolve about the axis 3 50 in the direction denoted by the arrow 1. The grain or the like to be dealt with bears up against a portion of this cylinder, and that within a suitably built box 4, the open part of which is applied to the cylinder 2.

55 As the cylinder 2 revolves, the grain is taken along in an upward direction (in

which case it moves in the direction of rotation at a somewhat slighter speed than the roller surface) until it is caught up and caused to rise either by the curved transverse section 5 (Fig. 1) or by intervention of a roller 6 (Fig. 2) having a smaller diameter but a greater peripheral velocity than the cylinder 2. The grain then flows by its own proper weight on and above the upwardly ascending mass of grain, though in an opposite direction, back until it encounters the lower transverse wall 7 which serves to lead the grain once more toward the surface of the cylinder 2 whence it is again forced upwards. By these means, a continuous circulation of the grain within the box 4 is achieved, resulting in the material being brought in constantly repeating contact with the said cylinder and being operated upon in an absolutely uniform manner. The husking action is at the same time very favourably affected by the pressure which the upper layers, returning in an opposite direction, exert upon the lower, ascending layers.

The apparatus constructed in accordance with my invention may be operated either with a continuous or intermittent feed action, the box 4 being provided with suitable 85 charging and outlet openings for the material to be treated, as also with a hinged bottom 7 for the final discharge thereof.

In the modification disclosed in Fig. 4, there is arranged within the box 4 an additional cylinder 8, the arrangement of said cylinder 8 being such that the grain will meet with no impediment in the course of its continuous circulation in the direction denoted by the arrows. Cylinder 8, as will 95 be observed, is of smaller diameter than the working cylinder 2, and revolves positively within the ambient mass of grain or the like, carrying out the husking, sprouting or polishing operations in the same manner as 100 the cylinder 2 so that thereby the efficiency of the apparatus is considerably enhanced.

I claim:

1. The method which consists in causing granular material to be carried along in upward direction within a confined space by a rough rotary, cylindrical surface, causing said material to be caught by suitable means and to descend again on and above other raised material and to be gripped and raised once more by said surface.
2. In a device of the kind described in

combination, a rotary cylinder having a rough surface, a chamber applied to and covering about one fourth of said surface and an auxiliary rotary cylinder having a rough surface disposed within said chamber.

3. In a device of the kind described in combination, a rotary cylinder having a rough surface, a chamber applied to and

covering about one fourth of said surface and a cylinder on top of said first cylinder at the upper end of said chamber.

In testimony whereof I affix my signature.

JOSEF PROKOP.
